UNITED STATES PATENT OFFICE.

EMANUEL FOERSTER, OF NEW YORK, N. Y.

STONE-SAWING MACHINE.

SPECIFICATION forming part of Letters Patent No. 350,191, dated October 5, 1886.

Application filed March 31, 1886. Serial No. 197,972. (No model.)

To all whom it may concern:

Be it known that I, EMANUEL FOERSTER, a resident of New York city, in the county and State of New York, have invented an Improved Stone-Sawing Machine, of which the following is a full, clear, and exact description, reference being made to the accompanying drawings, in which—

Figure 1 represents a face view, partly in section, of my improved stone-sawing machine; and Fig. 2 is a detail cross-section of the saw-blade.

This invention has for its object to improve the construction of the reciprocating saw-blade which is used in machinery for cutting stone, the invention being applicable to the kind of blade which cuts with the aid of sand, shot, or the like.

The invention consists, principally, in making the upper part of the blade of three or more thicknesses of metal, the outer thicknesses being of steel or other hard substance and the central thickness of soft metal. With this blade is combined a lower rotating twisted bar, which, as the blade to which it is attached is reciprocated, is revolved to agitate the sand or shot by which the cutting is done, all as hereinafter more fully described.

In the drawings, the letter A represents the upper part or body of the cutting-blade, which is made of three or more thicknesses, *a a* and *b*, of metal, the outer thicknesses, *a a*, being of steel or other hard substance, and the central thickness or thicknesses, *b*, of softer metal—such as iron.

B is the lower part of the blade, which is a bar of twisted iron or steel, and hung in straps *d*, that connect it with a nut, *x*. The bar B is twisted so as to form short spiral convolutions, as is clearly indicated in the drawings, and carries at its ends bevel gear-wheels *e*, that mesh into bevel-pinions *f*, which are supported by upright shafts C C, that have their bearings in the frame D, which carries the blade A B. The upper ends of the shaft C have toothed wheels *g*, that mesh into stationary racks *h*, which are supported by the fixed frame-work E of the machine.

The sliding frame D has rollers *i*, which support it on the stationary rails *j*. A pitman, F, from a driving shaft connects with

the frame D, to reciprocate it on the rails *j*. While the frame D is reciprocated the toothed wheels *g* are revolved and transmit rotary motion to the twisted bar B, which forms the lower part of the blade.

As the blade descends into the stone to be cut, by the means hereinafter stated, the twisted bar B remains in gear with the bevel-pinions *f*, by reason of their being arranged to slide on the shafts C—that is to say, each pinion *f* is free to slide on its shaft C, but connected thereto by feather and groove, so as to be revolved by the same.

I have shown each end of the twisted bar B to be geared into a shaft C; but the ends of my invention will be attained if only one such connection be established sufficient to cause rotation of the twisted bar B.

The blade A B is suspended in the reciprocating frame D from upright screws *k*, which carry bevel-pinions *m* at their upper ends in gear with similar pinions on a horizontal shaft, H. Whenever this shaft H is turned, by hand or automatically, the screws *k* will be turned to feed the cutting-blade A B down during the progress of the work.

The twisted bar B is coiled in such a fashion as to be wider than the blade A above it, so that, as is shown in Fig. 2, the blade A will never be in contact with the stone. The twisted bar B serves to agitate and move about the particles of sand or shot which are to perform the cutting operation. The twisting of the bar B serves to keep the particles of sand or shot constantly in action, and to therefore present new cutting-surfaces continuously to the stone.

By making the central thickness or thicknesses of the blade A of substantially soft substance I prevent the particles of sand or shot from being carried by the twisted bar into the space between said bar and the blade A—that is to say, the lower edges of the steel blades *a* are notched, as shown in Fig. 1, to fit the spiral form of the rotating bar B, so that sand or shot cannot get between the parts A and B.

The soft-metal central portion, *b*, of the blade A will allow the twisted bar B to form a convenient groove in the lower part of A, in which the upper part of B can revolve.

When I mention in this specification a "reciprocating blade" I mean one which reciprocates in the act of cutting the stone, and do not mean that the said blade should not also have an up-and-down motion at the end of each stroke.

Nothing herein contained is intended to claim means for reciprocating the blade-carrying frame D, nor the character of the motion 10 which the same receives.

What I claim is—

1. The stone-cutting blade constructed of the upper part, A, having cheek-pieces *a a* and middle piece, *b*, and lower twisted bar, B, 15 the piece *b* being of softer metal than the pieces *a*, substantially as herein shown and described.

2. The stone-cutting blade constructed of the upper part, A, having hard-metal cheek-pieces and softer middle piece, and of the 20 lower twisted bar, B, and means, substantially as described, for revolving said bar and reciprocating said blade simultaneously, as described.

3. The upper part, A, of the saw-blade, constructed of three or more thicknesses, *a b a*, 25 the central thickness being of softer metal than the outer thicknesses, in combination with the lower twisted bar, B, as specified.

EMANUEL FOERSTER.
